UNITED STATES PATENT OFFICE.

FRED C. OLIN, OF BUFFALO, NEW YORK, ASSIGNOR TO THE OLIN GAS ENGINE COMPANY, OF SAME PLACE.

IGNITER FOR GAS-ENGINES.

SPECIFICATION forming part of Letters Patent No. 592,881, dated November 2, 1897.

Application filed December 7, 1896. Serial No. 614,681. (No model.)

To all whom it may concern:

Be it known that I, FRED C. OLIN, a citizen of the United States, residing at Buffalo, in the county of Erie and State of New York, 5 have invented a new and useful Improvement in Igniters for Gas-Engines, of which the following is a specification.

This invention relates to an electric igniter for gas, petroleum, and similar engines, and 10 has for its object to produce an igniter for this purpose which is simple and reliable in operation and which insures the production of an effective spark regardless of the speed of the engine.

15 In the accompanying drawings, Figure 1 is a side elevation of a gas-engine provided with my improved electric igniter. Fig. 2 is a vertical longitudinal section, on an enlarged scale, of the preferred form of my improved 20 igniter. Fig. 3 is a cross-section in line 3 3, Fig. 2. Fig. 4 is a perspective view of the stationary contact and its support.

Like letters of reference refer to like parts in the several figures.

25 A represents the base of the engine, B the working cylinder, C the valve-chest communicating with the working-cylinder, D the crank-shaft, and E the governor-wheel geared with the crank-shaft, all of which parts may 30 be of any suitable and well-known construction.

F represents a supporting sleeve or tube which is arranged in an opening in the valve-chest so that a portion of the tube projects 35 inside of the chest and a portion outside of the chest. The tube may be secured to the chest in any suitable manner, preferably by providing the tube with a screw-thread and engaging the same with a screw-thread formed 40 in the opening in the valve-chest. The supporting-tube, or any part of the engine which is in metallic connection with the tube, is connected by a wire g with one pole of an electric generator G.

45 H represents a stationary electric contact supported on the inner end of the supporting-tube and forming the electric terminal of that pole of the generator with which the supporting-tube is connected. The latter and the 50 stationary contact are preferably detachably connected by means of an internally-screw-

threaded collar h, engaging with an external screw-thread on the inner end of the supporting-tube and provided with a cross-piece or bridge h', to which the stationary contact is 55 secured.

I is a guide-sleeve arranged within the supporting-tube and provided at its inner end with a head or enlargement i, which bears against the inner end of the tube, and at its 60 outer end with an external screw-thread, which receives a screw-nut i', bearing against the outer end of the supporting-tube. The guide-sleeve together with its head and screw-nut are separated from the opposing 65 parts of the supporting-tube by an intervening insulation i², so that these parts are not in electrical connection. The screw-nut or other part in electric connection therewith is connected by a wire i³ with the other pole of the 70 electric generator.

J represents a reciprocating guide-rod sliding in the guide-sleeve and its screw-nut and provided at its inner end with a head j, which carries a movable electric contact j' and which is adapted to engage with the inner end of the guide-sleeve to limit the outward movement of the guide-rod J. The latter is in electrical connection with the guide-sleeve, so that upon pushing the rod inwardly until 80 its contact bears against the stationary contact the electric circuit is completed, and upon withdrawing the guide-rod the contacts are separated and an electric spark is produced which ignites the gas in the valve-chest 85 and in the working cylinder. The contacts are normally held out of engagement with each other by a spring j², surrounding the guide-rod and bearing with its ends against the screw-nut on the outer end of the guide-sleeve and a screw-nut j³ on the outer end of 90 the guide-rod.

K represents an elbow-lever, whereby the guide-rod is moved inwardly for bringing the contacts together and which is pivoted to the 95 lower end of a hanger K', secured to the supporting-sleeve. The lower horizontal arm k of the elbow-lever is provided with a dovetail or undercut recess k', which receives a dove-tailed block k², of vulcanite or similar insulating material, which bears against the nut at the outer end of the guide-rod, thereby 100

preventing electrical communication between these parts. The upper end of the vertical upper arm k^3 of the elbow-lever is provided with a bearing-blade k^4 , which is secured thereto by a screw k^5 .

5 L represents a horizontal reciprocating trip or catch rod, which is provided at its front end with a hook or shoulder l , engaging with the blade at the upper end of the elbow-lever, 10 and whereby the latter is actuated. This catch or trip rod is guided in a movable yoke or carrier M and is provided on its front portion with a stop-collar m , which is adapted to bear against the front end of the yoke and 15 limit the rearward movement of the trip-rod in the yoke or carrier. The trip-rod is normally held in its rearmost position on the carrier by a spring m' , surrounding the rear portion of the trip-rod and bearing with its 20 ends against the carrier and a screw-nut m^2 on the trip-rod. The trip-rod is held against turning in the carrier by any suitable means, preferably by a lip m^3 , formed on the front end of the carrier and bearing against a flat 25 side m^4 on the stop-collar of the trip-rod, as represented in Figs. 2 and 3.

N represents a guide arm or standard which is formed on the hanger and which is provided at its upper end with a fork or bifurcation 30 between the arms n , of which the carrier is arranged. The under side of the carrier is provided with an inclined face o , which bears against an inclined face o' on the adjacent portion of the standard and which is adapted 35 to produce a rising-and-falling movement of the carrier while the latter moves lengthwise for the purpose of engaging the hook of the trip-rod with and disengaging the same from the elbow-lever.

40 The carrier and connecting parts are yieldingly held in their foremost position by a spring P, secured with its ends to the carrier and the standard N. The forward movement of the carrier and connecting parts is produced by a rock-lever Q, which is connected 45 between its ends by a rod q with the carrier and which is pivoted with its lower end to the base of the engine and provided at its upper end with a roller q' . The forward movement of the lever Q is produced by a 50 cam R, arranged on the governor-wheel and engaging with the roller on the lever, and the backward movement thereof is produced by the spring P. The cam rises gradually with its advancing or operative side r to the highest point and then declines gradually with its receding side r' , whereby the rock-lever 55 is operated without producing any noise.

In the rearmost position of the carrier and 60 trip-rod the carrier is in its lowermost position on the incline of the standard and the hook of the trip-rod is engaged with the blade of the elbow-lever.

65 During the first portion of the forward movement of the carrier the trip-rod moves with the same and turns the elbow-lever until the movable contact on the guide-rod has

been lifted into engagement with the stationary contact, whereby the electric circuit is completed and the further forward movement 70 of the guide-rod, the elbow-lever, and also the forward movement of the trip-rod for a time is arrested. During the second portion of the forward movement of the carrier the latter moves independent of the trip-rod, 75 thereby compressing the spring m' , and at the same time the carrier is raised by the co-operating inclined faces of the carrier and standard, whereby the trip-rod is disengaged from the elbow-lever and the latter and the guide-rod carrying the movable contact are quickly 80 returned to their normal position. By this means a quick separation of the contacts is effected and a powerful spark is produced for igniting the gas regardless of the speed of the 85 engine. This is particularly desirable when starting the engine, because at this time the parts are all moved slowly by hand or otherwise until the first ignition takes place. After the catch has been disengaged from the elbow-lever and the contacts have been separated the rock-lever Q continues its forward movement independent of the elbow-lever until the roller q' reaches the highest part of the cam R, after which the roller rides down 90 the receding portion of the cam and permits the rock-lever to move backwardly.

During the backward movement of the carrier the inclined front side of the hook on the trip-rod engages with the elbow-lever and lifts the trip-rod and carrier until the hook has passed in front of the elbow-lever, when the trip-rod and carrier drop into their normal position and the abrupt side of the hook engages with the front side of the elbow-lever 105 preparatory to producing the next spark.

By inclining both the front and the rear sides of the cam the parts cannot be injured by turning the governor-wheel backward, which otherwise would be liable to happen if only the front side of the cam were inclined 110 and the rear side made abrupt.

I claim as my invention—

1. In an igniter, the combination with the stationary contact and the movable contact, 115 of a lever whereby the movable contact is moved toward the stationary contact, a carrier having a back-and-forth and also a lateral movement, and a catch adapted to engage with said lever and yieldingly connected with 120 said carrier, substantially as set forth.

2. In an igniter, the combination with the support carrying a stationary contact, and the sliding rod guided in said support and provided with a movable contact, of a lever 125 having one of its arms engaging with said sliding rod, and a carrier having a back-and-forth and a lateral movement and provided with a catch adapted to engage with the other arm of the lever, substantially as set forth. 130

3. In an igniter, the combination with the support carrying a stationary contact, and a sliding rod guided on said support and provided with a movable contact, of a lever hav-

ing one of its arms engaging with said sliding rod, a carrier having a back-and-forth and a lateral movement, and a catch yieldingly connected with said carrier and adapted to engage with the other arm of said lever, substantially as set forth.

4. In an igniter, the combination with the support carrying a stationary contact, and a sliding rod guided on said support and provided with a movable contact, of a lever having one of its arms engaging with said sliding rod, a carrier having a back-and-forth and a lateral movement, a movable catch-rod guided in said carrier and provided with a hook adapted to engage with the other arm of said lever, a spring whereby the catch-rod is normally moved forwardly on the carrier, and a stop whereby the forward movement of the catch-rod on the carrier is limited, substantially as set forth.

5. In an igniter, the combination with the support carrying a stationary contact, and a sliding rod guided on said support and provided with a movable contact, of a lever having one of its arms engaging with said sliding rod, a carrier having a back-and-forth and a lateral movement, a movable catch-rod guided in said carrier and provided with a hook adapted to engage with the other arm of said lever, a spring whereby the catch-rod is normally moved forward on the carrier, a flat-sided stop-collar arranged on the catch-rod and adapted to engage with the carrier to limit its forward movement on the carrier, and a lip or projection arranged on the car-

rier and engaging with the flat side of the stop-collar, substantially as set forth.

6. In an igniter, the combination with a support provided with a stationary contact, and a sliding rod guided on said support and provided with a movable contact, of a lever having one of its arms engaging with said sliding rod, a carrier having a reciprocating movement and provided with a catch engaging with the other arm of said lever, and an incline formed on said carrier and engaging with an incline on said support, substantially as set forth.

7. In an igniter, the combination with a support carrying a stationary contact and a sliding rod guided on said support and provided with a movable contact, of an elbow-lever having one of its arms engaging with said sliding rod, a carrier having a reciprocating movement and provided with a catch engaging with the other arm of the elbow-lever, a rock-lever connected with said carrier, a cam and spring whereby said rock-lever and connecting parts are moved forwardly and backwardly, and coöperating inclines formed on the carrier and the support and adapted to move the carrier and connecting parts laterally, substantially as set forth.

Witness my hand this 27th day of November, 1896.
